UNITED STATES PATENT OFFICE.

LUMAN C. INGERSOLL, OF KEOKUK, IOWA.

TIMBER RAILROAD-TIE.

SPECIFICATION forming part of Letters Patent No. 530,778, dated December 11, 1894.

Application filed May 31, 1894. Serial No. 513,036. (No model.)

To all whom it may concern:

Be it known that I, LUMAN C. INGERSOLL, of Keokuk, in the county of Lee and State of Iowa, have invented certain new and useful 5 Improvements in Timber Railroad-Ties, of which the following is a full, clear, and exact description.

Reference is to be had to the accompanying drawings, in which—

10 Figure 1 is a perspective view illustrating the application of my invention, and Fig. 2 is a plan of the improved tie.

Like letters denote like parts in both the views.

15 The object of my invention is to provide a timber railroad tie that will be readily manufactured, and produced at less cost than metallic ties, while affording a high degree of safety against lateral displacement of the 20 track.

To this end my invention consists in a particular formation of the tie which will be fully disclosed hereinafter, and specifically pointed out in the appended claim.

25 The tie A illustrated by the drawings is provided with plane parallel top and bottom surfaces, the end surfaces a being arranged essentially perpendicular to the bottom or at any suitable angle thereto. The whole tie 30 consists of a single piece of wood.

My invention has especial reference to the formation of the side and top surfaces of the tie. The side surfaces are formed with portions b extending perpendicularly to the bottom, or approximately so, and inclined portions 35 spreading downward, as indicated at c. The portions b being arranged at a greater angle to the top or bottom than the portions c, shoulders d are formed between the said 40 portions. In consequence of the provision of the above inclined portions the top surface of the tie consists of a central spine e running lengthwise of the tie, and enlargements or shoulders f projecting on each side of the said 45 spine. The portions b of the side surfaces, and consequently, the enlarged portions f of the top surface, are placed at such a distance apart as will correspond to the width of the track, the rails R being adapted to rest on 50 the said enlarged portions, as will be seen in Fig. 1.

In practice the improved ties may be made from ordinary timber ties, by cutting out their lateral surfaces to form the inclined portions c, while the other surfaces are left intact, except as far as the cutting of the lateral surfaces involves an alteration of the top surface. It will be seen that the enlarged portions f 55 form ample bases for the support and fastenings of the rails, as the said portions extend the full width of the timber; also the full width of the bottom surface is preserved, so that the load that may rest upon the tie is distributed over a comparatively large surface of the ballast B. Furthermore, the shoulders d, being in intimate contact with the ballast packed between the ties, will effectively 60 prevent endwise movement of the ties, i. e., transverse displacement of the track, while by the provision of the inclined surfaces c and 65 the essentially vertical portions b between them, the ties are enabled to better resist the tendency of the rails to longitudinal movement, so that both longitudinal and transverse displacements of the track are prevented. 70

It will be understood that no skilled labor is required for the production of my improved ties, and that they therefore can be manufactured economically. 75

What I claim as my invention, and desire to secure by Letters Patent, is—

A timber railroad tie, consisting of a single piece whose top surface is composed of a longitudinal spine and enlargements projecting 85 on each side thereof at such a distance as will correspond to the width of the track, while the side surfaces of the tie comprise downwardly spreading inclined portions arranged both interiorly and exteriorly of the 90 said enlargements of the top surface, and portions of greater inclination relatively to the top surface of the tie than the said inclined portions and located between the inclined portions, whereby shoulders are formed on 95 the side surfaces of the tie, substantially as shown and described, and for the purpose set forth.

LUMAN C. INGERSOLL.
